UNITED STATES PATENT OFFICE.

EDGAR KETCHUM BETTS, OF TROY, NEW YORK.

DESIGN FOR A HIGH TURN-DOWN COLLAR.

SPECIFICATION forming part of Design No. 28,304, dated February 15, 1898.

Application filed December 11, 1897. Serial No. 661,563. Term of patent 14 years.

To all whom it may concern:

Be it known that I, EDGAR KETCHUM BETTS, a citizen of the United States, residing at Troy, in the county of Rensselaer and State of New York, have invented and produced a new and original Design for High Turn-Down Collars, of which the following is a specification, reference being had to the accompanying drawing, which shows a perspective view of the collar.

As shown in the drawing, the leading or material feature of my design consists of a high turn-down collar having extended lines A A', one of which, as A, is longer than the other end A'. This end A also has the up-

wardly - extending edge B, which projects above the fold-line C of the collar.

Having thus described my invention, what I claim as new, and desire to secure by Letters Patent, is—

The design for a high turn-down collar, as herein shown and described.

In testimony whereof I have signed my name to this specification in the presence of two subscribing witnesses.

EDGAR KETCHUM BETTS.

Witnesses:

JAS. M. SNYDER,
SAMUEL D. NICHOLS.
